UNITED STATES PATENT OFFICE

137,416

DESIGN FOR AN EMBROIDERED TRIMMING OR THE LIKE

Jack Wiener, New York, N. Y.

Application January 22, 1944, Serial No. 112,291

Term of patent 3½ years

To all whom it may concern:

Be it known that I, Jack Wiener, a citizen of the United States, residing in the Borough of Manhattan, city, county, and State of New York, have invented a new, original, and ornamental Design for An Embroidered Trimming or the like, of which the following is a specification, reference being had to the accompanying drawing, forming a part thereof, in which the figure in the drawing is a face view of a piece of embroidered trimming or the like embodying my new design.

I claim:

The ornamental design for an embroidered trimming or the like, as shown.

JACK WIENER.
